AUGUST A. KLANN, OF BASIC, VIRGINIA.

COMBINED MAGNET AND VALVE.

Application filed September 17, 1925. Serial No. 56,982.

This invention relates to improvements in pipe organs, particularly to the valve mechanism for controlling the passage of air to the pipes, and it consists of the constructions, combinations and arrangements herein described and claimed.

An object of the invention is to provide a relatively small instrument combining a valve and the electro-magnet for controlling it, several of the important features being a compact structure, the reduction of parts to a minimum number and the mode of assembling the parts on such order that disassembly for replacement and repair is readily accomplished.

Other objects and advantages will appear in the following specification, reference being had to the accompanying drawing, in which

20 Figure 1 is a cross section of a wind chest illustrating the installation of the improved combination magnet and diaphragm valve, the electro-magnet being deenergized with the result that the organ pipe is silent.

25 Figure 2 is a similar sectional view taken in a slightly different plane to illustrate the action upon energizing the electro-magnet, whereupon the organ pipe speaks.

Figure 3 is a horizontal section taken on 30 the line 3—3 of Figure 1,

Figure 4 is a horizontal section taken on the line 4—4 of Figure 1.

Figure 5 is a detail perspective view of the invention,

35 Figure 6 is a detail perspective view of the armature valve cover herein again referred to.

Figure 7 is a detail sectional view of the diaphragm valve and the puff which carries 40 it.

Figure 8 is a detail sectional view of a modification hereinafter referred to.

In carrying out the invention, provision is made of a base 1 which has a boss 2 rigidly 45 carrying the "hair pin" electro-magnet 3. The winding of the electro-magnet is included in a circuit comprising the generator G, the wire 4 which connects one side of the winding to one side of the generator, the wire 5 that connects the other side of the winding with a fixed contact 6 and a wire 7 that connects the other side of the generator with the movable switch 8. The switch may be associated with an organ key, the idea being 55 that a depression of the key will cause the

foregoing circuit to energize the electro-magnet.

The result of this energization will be the attraction of the armature 9. This armature is faced at 10 and 11 with skin. It is mounted upon a stud 11^a in the valve cover 12, its function being to either close the air opening 13 upon energization of the electro-magnet or to close the orifice 14. The latter function occurs when the electro-magnet is deenergized, the armature valve 9 then seating by gravity.

It is the purpose of the electro-magnet 3 and armature valve 9 to control the action, a valve 15 seating on the opening 16. In the 70 base 1, or upon the air outlet 17 and actuating through air control, a bellows valve admitting or closing off the admission of air to the organ pipe. The valve 15 seats on the opening 16 when the magnet is energized or 75 drops by gravity upon the air outlet 17 when the electro-magnet is deenergized. The former act permits exhaustion to atmosphere of air within the bellows 18 so that the organ pipe valve 19 uncovers the air opening 20 80 of the organ pipe 21, the latter act permitting an equalization of pressure between the interior of the bellows 18 and the interior of the wind chest 22 so that the bellows spring 85 23 causes seating of the valve 19 for the closure of the opening 20.

The valve 15 is composed of a fiber washer which is faced on opposite sides by felt, skin or other suitable washers 24 and 25. The valve stem 26 is threaded at 27 down to and slightly past the location of the air valve, (Fig. 7). The threads are utilized both to hold the valve and to permit such adjustment thereof as to location as may be required. The threads also support a fiber washer 28 at 90 the upper end. The puff or diaphragm 29 is secured to this washer.

A ring 30 clamps the diaphragm 29 at the periphery in position in the diaphragm or puff chamber 31. The diaphragm divides the 100 chamber into two, and the distinction is herein made by referring to one as the upper puff chamber, and the other as the lower puff chamber. The attachment of the valve stem to the diaphragm serves to guide the upper 105 end of the stem. The other end passes through a small bracket 32 (Fig. 5) which guides the lower end. The ring 30 is grooved at 33 (Figs. 1 and 3) to place the upper puff chamber into communication with a duct 34 110

in the base 1. The lower end of the duct communicates with the interior of the valve cover 12, and when the armature valve 9 is normally seated upon the orifice 14 the upper puff chamber contains air at wind chest pressure.

Communication between the lower puff chamber and the interior of the base 1 is had through a pair of passages 35 (Figs. 2, 3 and 4). These are divided by a bridge 36 (Fig. 4) 10 in which the duct 34 is bored or otherwise formed. The passages 35 are cut straight through the bottom of the base 1, but communication is not had with the atmosphere because the passages are covered by lateral flaps 15 37 of the armature valve cover 12 (Fig. 6).

Communication between the interior of the wind chest and the lower puff chamber through the passages 35 is permanent, and when the armature valve 9 is seated upon the 20 orifice 14, as stated before, air at wind chest pressure is obviously also present in the lower puff chamber. The equalized pressure on both sides of the diaphragm 29 permits the valve 15 to gravitate to its seating position 25 upon the air outlet 17. Air from the wind chest then enters the interior of the bellows 18 by way of the passages 35, the valve cap 38, bore 39 in the base 1 and bore 40 in the wind chest. The resulting equalization of 30 pressure inside and outside of the bellows permits the spring 23 to seat the valve 19.

Screws 41 at diagonally opposite corners of the base 1 (or elsewhere if desired) serve to secure the base upon the windchest 22. A gasket 35 42 (Figs. 1 and 2) is interposed. The wind chest has an opening 43 to admit the magnet 3. The cover 12 is held in place by a bent pin 44. The upper end of this pin is riveted at 45 (Fig. 3) to hold it in place upon the base 1. 40 The pin is intended to be turned over in position beneath the cover (Fig. 5) at which time it rides upon an arcuate enlargement 46 which permits a wedge action. Screws 47 (Fig. 4) hold the guide bracket 32 in place. A thin 45 wafer 48 of cardboard or other air sealing material fits upon the ring 30 to cover the upper puff chamber so that the security of this chamber need not rely upon the immediately surrounding portion of the gasket 42.

50 The operation is readily understood. The inoperative position is illustrated in Figure 1. The switch 8 is open and the electromagnet 3 is deenergized. The wind chest 22 contains air under pressure, and the armature valve 9 closes the orifice 14 both by virtue of the air pressure upon it and by gravity. The valve 15 also gravitates to the closed position upon the air outlet 17 in this manner: The opening 13 being uncovered admits air from 55 the wind chest to the interior of the cover 12 whence it enters the duct 34 and groove 33 and occupies the upper puff chamber. Air enters the lower puff chamber by way of the passages 35. The resulting equalization of pressure 60 at both sides of the diaphragm permits

the aforesaid gravitation. Under the same condition air also enters the interior of the bellows 18, as can readily be seen in Figure 1, so that there is equalization of pressure both on the inside and outside of the bellows. The 70 spring 23 therefore seats the valve 19 upon the opening 20 so that the pipe 21 is prevented from speaking. Upon depression of the switch 8, (which may be regarded as an organ key) the electro-magnet 3 becomes energized 75 by virtue of the closure of the electrical circuit. The armature valve 9 is then attracted to close the opening 13. This prevents the entrance of air under pressure from the wind chest 22 to the interior of the cover 12. Air 80 from the upper puff chamber therefore exhausts to atmosphere through the groove 33, duct 34, interior of the cover 12 and orifice 14. However, wind chest air pressure prevails in the lower puff chamber by virtue of the perpetual communication afforded by the passages 35. The unbalancing of the pressures causes the diaphragm 29 to rise (Fig. 2) so that the valve 15 is pressed up and over the opening 16. The valve is held in this position 85 by virtue of the predominating area of the diaphragm 29.

The foregoing action of the valve 15 uncovers the air outlet 17 so that the air in the bellows 18 exhausts to atmosphere. The resulting unbalancing of pressures causes the collapse of the bellows and the uncovering of the opening 20. Air under pressure then enters the organ pipe 21 and the pipe is caused 90 to speak.

One of the outstanding purposes of the invention is to produce a compact combined air control valve and magnet for controlling it. The instrument takes up but very little 105 more space than the average magnet, and this is a matter of no mean importance because space is generally a matter of serious consideration in pipe organ structure. Such air valves are usually of considerable size and are made separately from the electro-magnets 110 that control them. But here the parts have been so redesigned as to combine the elements into a relatively small space without sacrificing any original advantage.

In fact, the compacting of the elements 115 establishes new advantages. The closeness of the armature valve 9 makes it possible to operate the electro-magnet 3 with small current. Although the parts are firmly put together, they are, nevertheless, readily disassembled. The cover 12 is taken off by simply turning the bent pin 44 (Fig. 5). The cap 38 is removed by simply taking out the two screws 47 which hold the bracket 32 in place. The entire instrument is taken off by simply 120 removing two screws 41. It becomes an easy matter to repair any one of the instruments, it being remembered that many are used in the pipe organ.

Figure 8 illustrates a modification wherein 125

the pneumatic or bellows 18 is located outside of the wind chest 22 instead of on the inside as in Figures 1 and 2. The bellows is adapted to operate any desired action, but this is regarded as immaterial. In order to avoid a needless repetition, parts already described are designated by corresponding reference characters.

A valve stem 26 carries a pair of valves 49 and 50. These are collectively regarded as the air control valve. The upper valve 49 is housed within the base 1, and seats upon the opening 16. The lower valve 50 is exposed and seats upon the air outlet 17 of the cap 38.

Upon depression of the key 8 and closure of the electrical circuit illustrated so that the magnet 3 is energized, the resulting attraction of the armature valve 9 will, as above, cause an unbalancing of the pressures in the upper and lower puff chambers so that the diaphragm 29 raises into the position shown. The valves 49 and 50 are respectively unseated and seated. Air passes from the wind chest 22 to the interior of the bellows 18 and causes expansion thereof.

Release of the key 8 causes seating of the armature valve 9 upon the orifice 14. An equalization of pressures occurs on each side of the diaphragm 29 so that the diaphragm falls by gravity. The valves 49 and 50 will then respectively seat and unseat. Communication of the bellows 18 with the interior of the wind chest is cut off, and the bellows collapses.

While the construction and arrangement of the improved combined magnet and air control valve is that of a generally preferred construction, obviously modifications and changes may be made without departing from the spirit of the invention or the scope of the claims.

I claim:—

1. In an instrument of the character described, a base containing a chamber which has a diaphragm producing upper and lower puff chambers, a ring clamping the diaphragm in position having a groove through which communication is had to the upper puff chamber, a duct formed in the base communicating with the groove, and a bridge included in the base at the bottom of which the duct terminates for the independent supply of fluid under pressure to the upper puff chamber, said bridge defining a pair of passages establishing an independent pressure fluid conduit between the interior of the base and the lower puff chamber.

2. In an instrument of the character described, a hollow base having a bridge defining a pair of passages, a chamber formed in the base containing a diaphragm which produces upper and lower puff chambers, said passages communicating with the lower puff chamber, a duct formed in the base passing through the bridge and communicating

with the upper puff chamber, a cover applied to an opening in the base through which opening and cover fluid under pressure is supplied to said duct and upper puff chamber, and lateral flaps on said cover fitting over and closing said passages, thereby completing said passages for the conduction of fluid under pressure from the interior of the base to said lower puff chamber.

3. In an instrument of the character described, a base having a chamber containing a diaphragm which produces upper and lower puff chambers, a ring clamping the diaphragm in position and having an air groove therein, a duct formed in the base supplying the groove and upper puff chamber with fluid under pressure, means by which the base is affixed to a wind chest there being an interposed gasket, and a wafer of air-sealing material imposed upon the ring, restricting the upper puff chamber and avoiding dependence upon the gasket for sealing said chamber.

4. In an instrument of the character described, a base for detachable application to the exterior of a wind chest having an opening and a bore, a cap on said base overlying and providing communication between the opening and bore and having an air outlet, a valve controlling said opening and outlet including a valve stem, a diaphragm situated in the base from which said valve stem and valve are suspended, said diaphragm forming a guide for the upper end of the stem, a bracket providing a guide for the lower end of the stem, and means including screws by which the bracket and cap are simultaneously secured upon the base.

5. In an instrument of the character described, the combination with a wind-chest having an air passage from a source of air under pressure to the exterior of the chest and a bellows connected to and operating an organ pipe valve, said bellows having an operating air passage to the exterior of the wind-chest, of a unitary pipe valve controlling mechanism comprising a base detachably mounted on the exterior of the valve chest and provided with valve controlled passages overlying and interconnecting the wind-chest and the air passage of said bellows, an electro-magnet and armature valve mounted in said base with the armature valve movable by said magnet to close the passage through the base from wind-chest to bellows and by de-energization to open said passage, and a diaphragm valve mounted in said base and coincidentally operated by closure and opening of such passage to control the flow of air to and from said bellows.

6. In an instrument of the character described, the combination with a wind-chest having an air passage from a source of air under pressure to the exterior of the chest and a bellows connected to and operating an

organ pipe valve, said bellows having an operating air passage to the exterior of the wind-chest, of a unitary pipe valve controlling mechanism comprising a base detachably mounted on the exterior of the valve chest and provided with valve controlled passages overlying and interconnecting the wind-chest and the air passage of said bellows, an electro-magnet and armature valve mounted in said base with the armature valve movable by said magnet to close the passage through the base from wind-chest to bellows and by de-energization to open said passage, and a diaphragm valve mounted in said base and coincidently operated by closure and opening of such passage to control the flow of air to and from said bellows, said diaphragm valve being movable through unequal pressure against opposite sides of a diaphragm controlled and produced through movement of said armature valve, the latter being mounted in and seating over an air vent formed in a cover plate detachably clamped on said base and forming in part the passage interconnecting wind-chest and bellows.

AUGUST A. KLANN.
